CLAIM

The ornamental design for an aerial vehicle as shown and described.

DESCRIPTION

FIG. 1 is a front, upper, right perspective view of a first embodiment for an aerial vehicle of our new design in a first configuration;

FIG. 2 is a rear, lower, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and

FIG. 8 is a bottom view thereof.

FIG. 9 is a front, upper, right perspective view of the aerial vehicle of our new design in a second configuration;

FIG. 10 is a rear, lower, left perspective view thereof;

FIG. 11 is a front view thereof;

FIG. 12 is a rear view thereof;

FIG. 13 is a right view thereof;

FIG. 14 is a left view thereof;

FIG. 15 is a top view thereof; and,

(Continued)

FIG. 16 is a bottom view thereof.
